[57] **CLAIM**

The ornamental design for grid for poultry cage gate, as shown and described.

DESCRIPTION

FIG. 1 is a top plan view of a grid for poultry cage gate embodying my new design, the bottom being a mirror image of the top shown;

FIG. 2 is a right side elevational view thereof, the left side being the same as the right side shown;

FIG. 3 is a front elevational view thereof.

FIG. 4 is a rear elevational view thereof.

FIG. 5 is a cross sectional view taken on line 5—5 of FIG. 1.

FIG. 4

FIG. 1

FIG. 5

FIG. 3

FIG. 2
